UNITED STATES PATENT OFFICE.

ARTHUR MIDDLETON ROSE, OF YONKERS, ASSIGNOR TO THE W. & J. SLOANE, OF NEW YORK, N. Y.

DESIGN FOR CARPET-BORDER.

SPECIFICATION forming part of Design No. 24,463, dated July 2, 1895.

Application filed June 1, 1895. Serial No. 551,410. Term of patent 3½ years.

To all whom it may concern:

Be it known that I, ARTHUR MIDDLETON ROSE, a citizen of the United States, residing at Yonkers, county of Westchester, State of New York, have invented and produced a new and original Pattern for a Carpet-Border to be wrought in Woven Fabric—as, for example, in Wilton carpeting—in such colors as may be desired, of which the following is a specification.

In the accompanying drawing, which forms part of this specification, the characteristic features consist in the pattern, which shows oococo figures ranged in two bands along the length of the border and having ornaments of white flowers between. The mass of jet

black on one side of one of the bands, the closely-drawn fine vertical lines between the bands, and the heavier vertical lines on the opposite side of the other band merely indicate different backgrounds. 20

What I claim, and desire to secure by Letters Patent of the United States, is—

The design for a carpet border, substantially as shown. 25

Signed by me, in New York city, this 29th day of May, 1895.

ARTHUR MIDDLETON ROSE.
